UNITED STATES PATENT OFFICE.

FRANK H. FRANKENBERG, OF PUEBLO, COLORADO.

ORE-WASHER.

SPECIFICATION forming part of Letters Patent No. 764,448, dated July 5, 1904.

Application filed January 9, 1904. Serial No. 188,277. (No model.)

To all whom it may concern:

Be it known that I, FRANK H. FRANKENBERG, a citizen of the United States, and a resident of Pueblo, in the county of Pueblo and State of Colorado, have invented a new and Improved 5 Ore-Washer, of which the following is a full, clear, and exact description.

This invention relates to improvements in machines for washing ores and similar substances, an object being to provide a washer of very simple construction so arranged as to be operated with comparatively little power.

A further object is to so construct the device that it may be placed and operated at the bottom of a dump, where there is no natural flow or pressure of water.

Other objects of the invention will appear in the general description.

I will describe an ore-washer embodying 20 my invention and then point out the novel features in the appended claims.

Reference is to be had to the accompanying drawings, forming a part of this specification, in which similar characters of reference indicate corresponding parts in all the figures.

Figure 1 is a side elevation of an ore-washer embodying my invention. Fig. 2 is a perspective view illustrating pairs of buckets employed. Fig. 3 is a sectional elevation of 30 the washer. Fig. 4 is an end elevation, partly in section. Fig. 5 shows a shaking-cam employed. Fig. 6 is a detail showing the position of a pair of buckets when dumping material from one bucket to the other. Fig. 7 is a cross-section through one of the water-distributing pipes, and Fig. 8 is an elevation 35 showing supplemental tanks that may be employed.

Referring to the drawings, 1 designates a 40 tank in which is an endless carrier belt or apron 2. This belt is inclined upward toward its outlet end, so as to retain as far as possible fine particles of ore, so that the same may be washed off by the water in the tank as the carrier moves. The carrier-apron extends 45 around a roller 3 at the forward end of the tank and around a roller 4 at the rear end of the tank. Attached to the inner side of the carrier at about the center is a sprocket-chain 50 5, which engages with sprocket-wheels 6 7,

respectively, arranged on the rollers 3 4. Motion is imparted to the roller 3, and consequently to the carrier, through the medium of a driving-shaft 8. Extended from opposite sides of the tank near the receiving end 55 of the carrier are standards 9, connected at the top by a cross-bar 10, and supported on this cross-bar is a water-tank 11. Communicating with the tank and extending downward at the front and rear sides of the standards are water-distributing pipes 12 13. The pipe 12 has a horizontally-disposed section 14, while the pipe 13 has a horizontally-disposed section 15. These horizontal sections are perforated to discharge water onto the ore, as 60 will be hereinafter described. The lower ends of the pipes 12 13 are indicated as closed.

It may be here stated that in practice the tank 1 communicates through pipes 16 17 with a series of supplemental tanks 1^a 1^b, arranged 70 on lower planes, so that the muddy water will pass from one tank to the other, giving the same a chance to settle the mud on the bottom, so that clear water may be pumped from the lowermost tank through a pipe 18 into the 75 pressure-tank 11. By this means it will be seen that the water may be used over and over again, thus particularly adapting the machine to places where water is scarce.

Mounted in bearings secured to the rear 80 sides of the standards 9 near the upper end is a shaft 19, on which are sprocket-wheels 20, and mounted in bearings on the front side of the standards near the lower end is a shaft 21, secured to which are sprocket-wheels 22, and 85 engaging with these sprocket-wheels are sprocket-chains 23, to which opposite ends of the carrying-buckets are secured. The buckets are of perforated or open-mesh material, so that water may readily pass through the 90 same, and the buckets are arranged in pairs, whereby at a certain time ore or other material may be dumped from one bucket into the other of the pair. While I have illustrated but three pairs of buckets, it is to be understood that several pairs will be arranged at suitable intervals. Each pair consists of a bucket 24 and a bucket 25, which are reversely arranged—that is, with the opening or outlet 95 of one bucket adjacent to the opening of the 100

other bucket. The buckets of a pair, it will be noted, are made of different shapes. The bucket 24, which may be termed the "upper" bucket, because it carries the ore upward and 5 dumps upon turning into the other bucket, is substantially V-shaped in cross-section—that is, its front and rear walls are of equal size and are arranged at an angle to each other of approximately forty-five degrees. The 10 other bucket 25, however, has its inner wall somewhat shorter than the outer wall, so that the outer wall has a somewhat greater extension outward or approximately a sixty-degree angle, the object being to provide some extended space to catch the ore from the upper 15 bucket as the two buckets pass over the upper sprocket-wheels, and thus prevent spilling. The buckets are driven through the medium of a band 26, passing around a pulley 20 27 on the shaft 8 and around a pulley 28 on an outward extension of the shaft 19.

Arranged at the front of the tank 1 is a feeding-chute 29, which is inclined downward and has at its upper portion at the bottom a 25 screen 30, through which fine ore which requires no washing may pass and be sifted. This chute has a vertical shaking motion, and therefore it has swinging connection with a rod 31, secured to the upper ends of arms 32, 30 attached to the front end of the tank 1. A crank-lever 33 is mounted to rock on an extension of the shaft 21, and its upper or horizontally-disposed member has pivotal connection 34 with the chute. Its downwardly-disposed member is provided with a wrist-pin 35 for engaging in a cam-slot 36, formed in a cam-wheel 37, attached to the shaft 8. It may be here stated that the feed-chute 40 may be omitted and the ore shoveled directly into the receiving-bucket 24 without departing from the spirit of my invention. In the operation of the machine, however, as disclosed the ore is shoveled into the shaking-chute and falls into the bucket 24, the said 45 bucket of course carrying the ore upward at the forward side of the sprocket-chains, and upon reaching the dump the bucket is reversed, as indicated in Fig. 6, so that the ore passes from the bucket 24 into the bucket 25. During the movements of the buckets jets of 50 water are discharged from the pipe-sections 14 15 onto the buckets, so that the water passes readily through the ore to clean the same, and this is aided by the dumping of the ore from one bucket into another, as by such dumping 55 the ore is somewhat shaken up or turned over in its particles. Water will also discharge from the lowermost pipe-section 14 onto the ore on the chute. The ore carried by the buckets will be discharged onto the carrier 2 and disposed over the end thereof. The ore need 60 not be continuously shoveled into the chute; but a certain amount may be placed therein which will be fed gradually to the buckets by the shaking motion of the chutes. The cleans-

ing-water, obviously, will pass into the tank 1 and from this tank to the lower tanks and back to the tank 11, as before described. Comparatively little power will be required to operate this machine, as the ore carried down at 70 one side will practically counterbalance the weight of ore at the upcoming side.

Having thus described my invention, I claim as new and desire to secure by Letters Patent—

1. An ore-washing machine comprising a 75 tank, standards extended upward therefrom, a water-tank supported at the upper ends of said standards, water-distributing pipes extended from the tank downward at the front and rear sides of the standards, the said pipes 80 having horizontally-disposed sections provided with perforations, carrier-chains supported by the standards, and buckets mounted on said chains, the said buckets being arranged in pairs of reverse order. 85

2. An ore-washer comprising a tank, standards extended upward from said tank, an endless carrier operating in the tank, a water-tank supported at the upper ends of said standards, pipes extended downward from said water-tank at the front and rear sides of the standards and having cross-pipes provided with perforations, sprocket-wheels having shaft-bearings at the upper portions of the standards, sprocket-wheels having shaft-bearings at the 95 lower portions of the standards, chains engaging with the sprocket-wheels, and perforated buckets attached to the chains, the said buckets being arranged in pairs and in reverse order whereby one bucket of a pair may dump 100 material into its companion bucket. 105

3. An ore-washer comprising an endless series of buckets, carrier-chains for said buckets, the said buckets being arranged in pairs, the buckets of a pair being of different shapes, 110 whereby the outer wall of one bucket has a greater degree of angle than the outer wall of its companion bucket, and means for discharging water onto the buckets during their movements. 115

4. An ore-washer comprising a tank, standards extended from the tank, a water-distributing tank supported by said standards, water-distributing pipes extended downward from said distributing-tank at the front and rear sides of the standards, sprocket-wheels having their shaft-bearings at the upper portions of the standards, sprocket-wheels having their shaft-bearings at the lower portions of the standards, chains engaging around said upper and lower sprocket-wheels, buckets arranged in pairs and attached to said chains, and a shaking-chute for discharging material into the buckets. 120

5. An ore-washer comprising a tank, a roller arranged in the tank near the forward end, a roller at the rear end of the tank and at a higher level than the first-named roller, an endless carrier engaging around said rollers, a sprocket-chain attached to the inner side of 125 130

said carrier, sprocket-wheels on the rollers for engaging with said chain, a series of carrying-buckets arranged vertically over said carrier, the said buckets being perforated, and 5 means for discharging water onto said buckets.

6. An ore-washer comprising a tank, standards on said tank, a water-tank supported by the said standards, water-distributing pipes extending downward from said last-named 10 tank and having perforated transverse sections, perforated carrying-buckets arranged in pairs between the front and rear distributing-pipes, a vertically-swinging feed-chute having a screen upper end, and a cam mechanism for causing the vertical swinging movements of said chute.

7. An ore-washer comprising a tank, standards on said tank, a water-tank supported by said standards, distributing-pipes extended

downward from the water-tank at the front 20 and rear sides of the standards, a series of ore-carrying buckets operating vertically between the front and rear distributing-pipes, an endless carrier in the tank, and a pipe for conducting clean water into the water-tank. 25

8. An ore-washer comprising a vertically-movable endless carrier, pairs of buckets on the carrier, the buckets of a pair being arranged in reverse order, and means for discharging water onto the buckets during their 30 upward and downward movements.

In testimony whereof I have signed my name to this specification in the presence of two subscribing witnesses.
